(57) **CLAIM**

The ornamental design for a dual input power supply as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a dual input power supply showing our new design;

FIG. 2 is a back view of a first embodiment thereof;

FIG. 3 is a left view of a first embodiment thereof;

FIG. 4 is a right view of a first embodiment thereof;

FIG. 5 is a top view of a first embodiment thereof;

FIG. 6 is a bottom view of a first embodiment thereof;

FIG. 7 is a front and left side perspective view of a first embodiment thereof;

FIG. 8 is a back and right side perspective view of a first embodiment thereof;

FIG. 9 is a front view of a second embodiment thereof;

FIG. 10 is a back view of a second embodiment thereof;

FIG. 11 is a left view of a second embodiment thereof;

FIG. 12 is a right view of a second embodiment thereof;

FIG. 13 is a top view of a second embodiment thereof;

FIG. 14 is a bottom view of a second embodiment thereof;

(Continued)

FIG. 15 is a front and left side perspective view of a second embodiment thereof;
 FIG. 16 is a back and right side perspective of a second embodiment thereof;
 FIG. 17 is a front view of a third embodiment thereof;
 FIG. 18 is a back view of a third embodiment thereof;
 FIG. 19 is a left view of a third embodiment thereof;
 FIG. 20 is a right view of a third embodiment thereof;
 FIG. 21 is a top view of a third embodiment thereof;
 FIG. 22 is a bottom view of a third embodiment thereof;
 FIG. 23 is a front and left side perspective view of a third embodiment thereof; and,
 FIG. 24 is a back and right side perspective of a third embodiment thereof.
 The evenly spaced broken lines shown in the figures contain lightly shaded areas that depict the portions of the dual input power supply that form no part of the claimed design. The design does not claim protection for a specific coloring.
